UNITED STATES PATENT OFFICE.

CHARLES H. LEARNED, OF MERIDEN, CONNECTICUT.

DESIGN FOR FUNERAL ORNAMENTS.

Specification forming part of Design No. **11,155**, dated April 15, 1879; application filed February 27, 1879.
[Term of patent 7 years.]

To all whom it may concern:

Be it known that I, CHARLES H. LEARNED, of Meriden, in the county of New Haven and State of Connecticut, have invented a new Design for a Funeral Ornament; and I do declare the following, when taken in connection with the accompanying illustrations, to be a full, clear, and exact description of the same.

The invention relates to a design for an ornament with special reference to funeral decoration—that is to say, an ornament which may be attached to a casket, or to a coffin, or to flowers, or to other parts of funeral decorations, and for analogous purposes; and it consists of the form and ornamentation of a lyre as the base, combined with a ribbon or band across its surface, the ends of which project at the sides of the lyre, as shown in the accompanying illustrations. On the face of the ribbon or band any words or an appropriate motto may be placed, as shown in the accom-

panying illustrations. The band is here represented as a ribbon, with projecting ends at the side of the lyre, as shown in the accompanying illustrations. The exact form of the band or ribbon is immaterial, it only being necessary that some form of a band or projecting surface rest across the surface of the lyre, and that the ends project beyond the sides of the lyre.

I claim—

The herein-described design for funeral ornament, consisting of the representation of a lyre, combined with the representation of a band or ribbon across its surface, the ends of which project at the sides of the lyre, as shown in the accompanying illustrations.

CHARLES H. LEARNED.
